UNITED STATES PATENT OFFICE.

BYRON A. BROOKS, OF BROOKLYN, NEW YORK, ASSIGNOR TO UNION TYPEWRITER COMPANY, OF JERSEY CITY, NEW JERSEY, A CORPORATION OF NEW JERSEY.

TYPE-WRITING MACHINE.

No. 812,782.

Specification of Letters Patent.

Patented Feb. 13, 1906.

Original application filed January 28, 1899, Serial No. 703,642. Divided and this application filed February 20, 1906. Serial No. 5,901.

To all whom it may concern.:

Be it known that I, BYRON A. BROOKS, a citizen of the United States, and a resident of the borough of Brooklyn, city of New York, 5 in the county of Kings and State of New York, have invented certain new and useful Improvements in Type-Writing Machines, of which the following is a specification.

The present invention relates, primarily, 10 to the type-bar and shifting-platen mechanisms of visible-writing machines.

One object of the invention is to pivot the type-bars so that they will lie normally obliquely to the horizontal plane of the machine 15 and swing rearwardly and downwardly and strike the platen at a common point between the topmost and foremost portions of the platen, preferably about midway of the front uppermost quadrant of the cylindrical 20 platen.

Another object of the invention is to provide type-bars with two or more types and to shift the platen obliquely to receive the upper-case characters.

25 Other objects will hereinafter appear.

To these ends the invention consists of certain features of construction and combinations of devices hereinafter more fully described, and particularly pointed out in the 30 appended claims.

The preferred form of the invention is illustrated in the accompanying drawings, forming part of the specification, in which—

Figure 1 is a plan view, on a reduced scale, 35 of a type-writing machine in which my improvements are embodied, there being but four type-bars shown, however, and the inking-ribbon and its operating mechanism and other parts being omitted. Fig. 2 is a central vertical longitudinal sectional view on a different scale and showing two type-bars and their operating mechanism, and Fig. 3 is a similar view with the platen in shifted position.

45 The same part will be found designated by the same numeral of reference in all views.

1 designates a suitable framework or base; 2, side arms or risers at each side of the base; 3 and 4, supports for type-bar hangers, the 50 said supports being in the form of segments of rings arranged to be concentric with the printing-point, the plane or planes of the seg-

ments being inclined to the horizontal and with their common center (or printing-point) above and to the rearward of said segments, 55 the said center or printing-point being at the upper front side of the platen, hereinafter described.

5 and 6 are standards by which the supports 3 and 4 are connected with the sides 60 and also with a cross-bar 7 of the base or frame 1; 8, overhanging brackets secured to the top plate of the base 1 at the rear and projecting forwardly of the machine, said brackets being united at their overhanging ends by a cross-bar 9, to which is secured a tubular bearing 10, extending longitudinally of the machine and at about the same angle to the horizontal as that formed by the type-bar supports 3 and 4.

11 and 11^a indicate, respectively, front and rear rods or tracks for the carriage, said tracks being parallel and extending transversely of the machine and being supported, respectively, by arms 12 and 12^a, projecting, 75 respectively, from shafts 13 and 13^a, which are journaled in the brackets 2 aforesaid. The arms 12 and 12^a are equal in length and project upwardly and forwardly of the machine from their respective shafts 13 and 13^a, and 80 said shafts are arranged with the rear one higher than the front one and parallel to each other, so that a plane passing through the axes thereof is parallel or substantially parallel to the planes of the type-bar supports 3 85 and 4.

14 indicates curved links pivotally connected at their ends with the ends of the rods 11 and 11^a, whence it results that the rods or ways 11 and 11^a move in unison about 90 their respective shafts 13 and 13^a and also move in equal arcs. The shaft 13 is provided with a rearwardly-extending arm 15, which is connected by a pivoted link 16 with an upper-case lever 17, pivoted at the rear of the base 1 and extending forward on the left-hand side of the machine to near the left-hand front corner, where it is provided with a finger-key 18. The platen-carrier consists of a carriage 19, formed of end pieces 20, a front bar 21, and an inverted-U shaped or channel bar 22 at the rear and three rollers 23, one of said rollers being at the front of the carriage and near the center thereof and the other two being at

the rear of the carriage and journaled within the bar 22, the said rollers being grooved to fit the round bars 11 and 11^a. One or more hooks or catches 24, secured to the bar 22 and bending under the rear bar 11^a, serve to prevent the carriage 19 from being accidentally removed from its tracks or guideways 11 and 11^a. The platen 25 is supported by a rod or shaft 26, which has bearings 27 in the ends 20 of the carriage. As shown, these bearings are open at the top, whereby the platen and its shaft may be removed at will from the carriage. Suitable sleeves 28 between the ends of the platen and the inner sides of the ends 20 of the carriage prevent endwise motion of the platen independently of the carriage.

From the described construction of the carriage-supporting and carriage-shifting mechanism and also the type-bar supports 3 and 4 it results that the platen is shifted from lower-case to upper-case position in a direction which is parallel or substantially parallel to the planes of the type-bar supports 3 and 4. As will hereinafter more fully appear, this direction of shift is parallel or substantially parallel to the plane of the faces of the two types on a type-bar when the types are at the impression-point, or, in other words, one of the platen and type-bar support members is constructed and arranged to shift obliquely in a plane coincident with or parallel to the oblique plane in which the type-bar pivots are situated.

The carriage is provided with a rack-bar 29, extending lengthwise thereof and with its plane at an angle to the vertical, as indicated at Fig. 2. The rack 29 meshes with a broad pinion 30, fast on a shaft 31, which is journaled in the bearing 10 aforesaid and is provided at its rear end with a ratchet-wheel 32. Said ratchet-wheel may be loose upon the shaft and be connected therewith by means of a pawl and ratchet in a well-known manner. Feed and holding dogs 33 34, respectively, on a rocking dog-carrier arm 35 coact with the ratchet-wheel 32 in a known manner to govern the motions of the carriage. The arm 35 is carried by a rocker or shaft 36, journaled under the top of the base 1, and the shaft is rocked or turned in one direction by a spring 37, fast at one end to the shaft and bearing at its other end under the top of base 1 in such wise that the arm 35 is moved rearwardly whenever the said spring 37 is permitted to rock the shaft. The carriage is moved toward the left by means of a spring-drum 38 and a strap 39, connecting the drum with an arm 40 on the carriage.

41 indicates horizontal key-levers provided with finger-pieces 42; 43, a rod at the rear of the machine and secured to the base 1 and against which the key-levers bear by means of notches 44 in their upper edges; 45, spiral springs attached at their lower ends to the levers 41 and at their upper ends to bent

arms 46, projecting forwardly from a sleeve 47, fast on a shaft or rod 48, which is secured to the top of base 1 by bearings 49. The sleeve 47 and arms 46 are formed from one piece of metal, which before the bending of the arms and the formation of the sleeve resembles a comb. The upward motion of the key-levers 41 is limited by the bar 43 and a buffer or stop-bar 50 under the cross-bar 7 aforesaid. Each key-lever 41 is provided with an overhanging extension 51, which engages with the upper side of a universal bar 52, the distance between the overhang and the key-lever being such that the universal bar may be moved by any one overhang 80 to the extent due to the full depression of the corresponding key-lever without coming in contact with the top of any key-lever or the part connecting with the overhang 51. The universal bar 52 is connected with the shaft 85 43 by means of arms 53 and jaws 54, secured to the arms 53 by screws 55. An upwardly-projecting arm 56 is attached to the universal bar and is pivotally connected at 57 with a forwardly and downwardly extending arm 90 58, which is pivoted to a projection on the front of rocker-arm 35 aforesaid.

The type-bar hangers herein shown each comprise two parallel connected arms 59 and two parallel downward extensions 59^a. The hangers are secured to the supports 3 and 4 by screws 60, which pass between the arms 59 and enter threaded holes in said supports, the flat heads of the screws or washers thereunder bearing upon the top edges of the arms. 100 Each hanger is provided at or near the bend thereof with appropriate bearings 61 for the coned arbors 62 of type-bars 63. The pivotal points of the type-bars 63 are in front of and below the level of the printing-point on the platen and the type-bars in normal positions flare upwardly and outwardly of the machine. The arms 59 of the type-bar hanger may be adjusted relatively to each other, so as to regulate the pressure of the bearings 61 110 against the pivots 62 in any suitable manner, as by screws 64, which pass freely through the hole in one arm and engage a threaded hole in the other arm in a well-known manner. As shown in the drawings, the bend or 115 angle of each type-bar hanger, which is secured to the support 3, points upwardly and its arms 59 project upwardly and rearwardly from the support and the extensions 59^a project downwardly and rearwardly, while the point or angle of each type-bar hanger which is secured to the support 4 points forwardly 120 of the machine and the arms 59 thereof project forwardly and downwardly from the support 4 and the extensions 59^a project 125 rearwardly and downwardly. In both cases the type-bar hangers are arranged radially with respect to the printing-point. The type-bars 63 are preferably each provided with a type-block 65, having two type or 130

characters thereon, and each type-bar is provided with a circular rack or toothed geared segment 66, and the arbor or axis of motion 62 of the type-bar is eccentrically placed 5 with respect to said gear or segment 66. The type-bar hangers are provided near the free ends of the extension 59^a with bearings 67 for the coned arbors 68 of bell-levers 69.

One arm 69^a of each bell-lever 69 is provided with a curved rack-segment 70, and the arbor 68 is eccentric with respect to the center of the said segment 70. The eccentric gearing 66 and 70, connecting the arm 69^a with the lever 63, is so arranged that when 15 the type-bar is in normal position (see Fig. 2) the leverage upon the type-bar is greatest and so that when the type-bar is in position in which its type impacts upon the platen the leverage upon the type-bar is least.

20 Preferably the relative radii of the gears 66 and 70 are such that the type-bar swings through an angle nearly three times as great as that through which the bell-lever swings, though of course these proportions may be 25 varied to suit different cases or as may be desired. The arms 69^b of the bell-levers 69 project forwardly of the machine, (the key-levers 41 being pivoted at the rear of the machine,) but are radial with respect to the 30 printing-point and are provided with two perforations 71 72. Connecting-rods 73 are pivotally connected with arms 69^b by means of said perforations 71 (or 72) and with the key-levers 41. The type-bars normally lie 35 against a padded support 74.

The operation of the type-bar movement is as follows: Upon the depression of a key 42 the corresponding lever 41 is moved downwardly and the arm 69^b of the corresponding bell-lever is pulled downwardly by the connecting-rod 73. The upwardly-extending arm 69^a of the bell-lever is moved forwardly of the machine, acting at that time with the maximum of leverage upon the gear 66 and 45 type-bar 63, thus securing an easy start of the type-bar toward the printing-point, and as the motion of the bell-lever is continued the speed of the type-bar is continually increased (even though the bell-lever should 50 continue to move at a uniform speed) until such time as the type-bar strikes the platen, at which moment the type-bar reaches its maximum speed. On the release of the depressed key-lever the corresponding spring 55 45 raises the key-lever, and the lever through the connecting-rod 73 reverses the direction of motion of the bell-lever 69, and the bell-lever through the described gearing moves the type-bar away from the platen quickly. 60 During the depression of a key-lever 41 the universal bar 52 is drawn down and the arm 35 is drawn forward by the described connections with the universal bar, thus bringing the holding-dog 34 into engagement with the escape-wheel 32. On the release of the key 65

the arm 35 is moved rearwardly by the spring 37 to bring the feed-dog into engagement with the ratchet-wheel 32, and the carriage is moved forward one letter-space distance by the spring-drum in the usual manner. Upon 70 the depression of the upper-case key the tracks 11 and 11^a are shifted from the position shown in Fig. 2 to that shown in Fig. 3 and the platen is moved in a direction parallel or substantially parallel to the plane of faces 75 of the two types on the type-bar when the types are at the impression-point. The rack 29 remains in mesh with the gear 30, but slides axially of the gear to a position different from that shown in Fig. 2. 80

It is observed that the type-bar is not upon a dead-center in any position in which it is moved by the toothed gearing described and that since the action of the gearing 66 and 70 is in the plane of the type-bar there is little 85 or no side strain on the type-bars. By the provision of the eccentric gearing for operating the type-bars it is possible not only to move the type-bars through greater angles even than ninety degrees, but also to get 90 them to flare upwardly and outwardly of the machine to such an extent that the operator when sitting in natural position, or that assumed for operating the keys of the machine, may see the entire line of print upon the 95 platen without moving from such position. The line of print is upon the front and upper side of the platen in better view than if on top of the platen or at its front, it being assumed that the ribbon is automatically or 100 otherwise removed from over the printing-point for the purpose of affording a clear view of the written line. It is also observed that since the arms 59 of the type-bar hanger are parallel and that since the extensions 59^a and 105 arms 59 are at right angles to each other a single screw 64 suffices for adjusting the pressures of the arms and extensions upon the pivots of the type-bar and of the bell-lever.

The rearward shifting movement of the 110 platen-carrier 19 may be limited by set-screws 77, which engage threaded holes in lugs or ears on the brackets 2 and against which the links 12 may contact or strike, while the normal position of the platen-carrier may be defined by similar set-screws 78, engaging with 115 threaded holes in lugs or ears on the brackets 2 and contacting with links or arms 12.

It will be observed that the machine contains a series of pivoted horizontally-disposed 120 key-levers extending under an endwise-movable carriage and to the front of the machine, a platen mounted on the carriage and movable transversely to the line of travel thereof and obliquely to the horizontal plane of the 125 machine, mechanism for moving the platen transversely at will; a series of type-bars pivoted in front of the platen and below the horizontal plane thereof or below the horizontal plane of its under side, and that said 130

type-bars are normally inclined away from the platen toward the front of the machine and provided with a plurality of characters on each bar, and that there are suitable operative connections between each type-bar and its associated key-lever. It will also be perceived that the type-bars are pivoted in an arc or on a segment which lies in an oblique plane, that the links or rocker-arms 12 and 12^a, which extend upwardly and forwardly from the parallel horizontal rock-shafts 13 and 13^a, support the platen and enable it to shift obliquely, and that the rails or tracks 11 and 11^a, to each of which the platen-frame is independently hinged, are shiftable together obliquely. The axes of the said hinges are parallel with each other and with the platen-axis, and all of said axes are preferably independent of one another. The platen-frame returns to normal position by gravity. The horizontal key-levers 41 are of the second order and extend side by side rearwardly from the keyboard beneath the platen-frame and the type-operating levers 63 and 69. Each set of said type-operating levers is pivoted in an obliquely-disposed arc or segment. The links 73 extend downwardly and rearwardly from the type-operating levers 69 to the key-levers and diverge or fan out at their lower ends because of the relative arrangement of the type-operating levers and the key-levers, the latter taking up more room widthwise of the machine than the type-operating levers. Furthermore, it will be seen that each rigid or single-piece type-bar swings on a single pivotal center and that the types are rigidly secured thereto and face rearwardly when the bar is in the normal position.

The type-bar mechanism *per se* is made the subject-matter of a patent granted to me March 26, 1901, No. 670,699, and hence is not claimed herein specifically. This application is a division of the application on which said patent is issued.

What I claim as new, and desire to secure by Letters Patent in this case, is—

1. The combination of an endwise-movable carriage, a platen mounted thereon, and movable transversely to the line of travel and obliquely to the horizontal plane of the machine, means for at will so moving the platen transversely, a series of pivoted horizontally-disposed key-levers extending under the carriage and to the front of the machine, a series of type-bars pivoted in front of the platen below the horizontal plane thereof and each of which swings on a single pivotal center, and normally inclined away from the platen toward the front of the machine, a segment arranged obliquely to a horizontal plane and on which said type-bars are pivoted, two or more characters rigidly secured to each type-bar and operative connec-

tions between each type-bar and its corresponding key-lever.

2. The combination of a platen, movable endwise and transversely in a plane oblique to the horizontal plane of the machine, means for at will moving the platen obliquely, transversely, a series of type-bars pivoted in front of the platen and each swinging on a single pivotal center and having more than one character thereon, a segment arranged obliquely to a horizontal plane and on which said type-bars are pivoted, a series of horizontally-disposed key-levers pivoted at the rear of the machine and extending forward under the platen and type-bars, and operative connections between each key-lever and its corresponding type-bar.

3. In a type-writing machine, the combination of type-bars each provided with a plurality of type, projecting rearwardly when the type-bar is in the normal position, said type-bars being pivoted in an arc oblique to the horizontal and each type-bar swinging on a single pivotal center and striking rearwardly and downwardly, a platen arranged with its printing-point between the top and the front thereof, and a platen-carriage arranged to vibrate in a line parallel with the type on the type-bars at the point of impression.

4. In a type-writing machine, the combination of a platen-carriage, a guide-rail upon which said platen-carriage is hinged, a second rail upon which said carriage is independently hinged, said carriage being constructed and arranged to travel along upon said rails, links or arms connected to said rails and pivoted upon the frame of the machine, a shifting key-lever, and a connection between said lever and said rails for vibrating the latter to shift the platen in a line with the types at the point of impression, at any portion of the endwise travel of the carriage along said rails.

5. In a type-writing machine, the combination of a platen, type-bars provided with a plurality of type and pivoted in front of and below the level of the printing-point at the upper front side of the platen and the plane of the type-faces on a type-bar when the type are at the impression-point being oblique to the horizontal, parallel guide or track rails for the platen-carrier arranged in a plane oblique to the horizontal, rock-shafts and arms supporting said track-rails, said rock-shafts being arranged in a plane oblique to the horizontal and all said planes being parallel or substantially parallel to each other, and means for rocking one of said rock-shafts to vibrate the platen into positions for coaction with said type upon the type-bars.

6. In a type-writing machine, the combination of a front guide-rail at one level, a rear guide-rail at a higher level, a platen having

the printing-point at its upper front side, a platen-carriage traveling on said guide-rails, type-bars provided with a plurality of type and pivoted in an arc or arcs parallel or substantially parallel with the plane of said 5 guide-rails and striking rearwardly and downwardly, and mechanism for shifting said carriage-guide rails and platen-carriage in or substantially in the direction of the plane of 10 said type when they are at the impression-point.

7. In a type-writing machine, the combination of type-bars provided with a plurality of type and pivoted in an arc or arcs oblique 15 to the horizontal and striking rearwardly and downwardly, a platen arranged with its printing-point between the top and the front thereof, a power-driven platen-carriage arranged to vibrate in a line parallel or substantially 20 parallel with the plane of the type on the type-bars when at the point of impression, a rack-bar connected with the carriage and having its plane at right angles to the direction of shift of said carriage, an oblique shaft on the main frame, a pinion on said shaft engaging with said rack-bar, an escapement for controlling said shaft, finger-keys, and connections between said keys and type-bars and said escapement.

30 8. In a type-writing machine, the combination of a platen arranged with its printing-point between the top and the front thereof, a power-driven platen-carriage arranged to vibrate in a direction oblique to the horizontal, a rack-bar connected with said platen-carriage and having its plane at or substantially at right angles to the direction of vibration of said carriage, a shaft journaled in the main framework and having a gear-wheel engaged with said rack, an escapement for controlling said shaft, and key-operated type mechanism having type adapted to coact with the platen in the normal and the shifted positions thereof.

45 9. In a type-writing machine, the combination of a horizontally-traveling platen-carriage, parallel front and rear guide-rails therefor, two pairs of obliquely-arranged arms connected to said guide-rails, at their upper ends and pivotally mounted at their lower ends, means for swinging said pairs of arms and said guide-rails, and thus shifting the carriage and platen, and type-bars provided each with a plurality of types and pivotally mounted so as to strike the platen at a common center at a point between its frontmost side and its topmost side.

55 10. In a type-writing machine, the combination of a platen, a series of pivoted type-bars each provided with a plurality of types rigidly secured thereto, said type-bars being pivoted in an arc which lies in an oblique plane, and being constructed and arranged to strike between the top and front of the 60 platen, a shift-key, and connections between

said shift-key and said platen constructed and arranged to enable the platen to shift obliquely and in a plane coincident with or parallel to the oblique plane in which the type-bar pivots are situated.

70 11. The combination of the platen movable endwise and also transversely in a plane oblique to the horizontal plane of the machine, means for at will moving the platen transversely, a series of type-bars pivoted in front of the platen, the pivots of the type-bars being situated in one or more planes oblique to a horizontal plane and each type-bar having more than one character thereon, a series of horizontally-disposed key-levers 80 pivoted at the rear of the machine and extending forward under the platen and type-bars, and a series of angular levers or bell-cranks pivoted below the type-bars and each operatively connecting a key-lever with its 85 corresponding type-bar.

12. The combination of an endwise-movable carriage, a platen mounted thereon and movable transversely to the line of travel and in a direction inclined to a horizontal plane, 90 means for at will so moving the platen transversely, a series of pivoted horizontally-disposed key-levers extending under the carriage and to the front of the machine, a series of type-bars pivoted in front of the platen below the horizontal plane thereof and each of which swings on a single pivotal center, and normally inclined away from the platen toward the front of the machine, a segment arranged obliquely to a horizontal plane and on 100 which said type-bars are pivoted, two or more characters rigidly secured to each type-bar and operative connections between each type-bar and its corresponding key-lever.

13. The combination of a platen traveling 105 endwise and movable upon pivoted parallel link connections upwardly and rearwardly in a plane oblique to the horizontal plane of the machine, means for at will so moving the platen obliquely and permitting its return by 110 gravity, a series of type-bars pivoted in front of and normally inclined away from the platen, a series of key-levers pivoted in rear of and extending forward under the type-bar pivots, and operative connections between the key- 115 levers and type-bars.

14. The combination of an endwise-movable platen mounted to be shifted transversely in a plane oblique to the horizontal plane of the machine, a series of pivoted type-bars each having more than one character thereon, in front of the platen and normally lying inclined toward the front of the machine and arranged to strike downwardly upon the upper front quarter of the platen, a 120 series of key-levers pivoted in rear of the type-bar pivots, a series of levers interposed between the type-bars and key-levers and operative connections between the interposed levers, key-levers and type-bars.

15. In a type-writing machine, the combination of a platen, a series of pivoted type-bars each provided with a plurality of types rigidly secured thereto, said type-bars being pivoted in an arc on a support which lies in an oblique plane, and being constructed and arranged to strike between the top and front of the platen, a shift-key and connections between said shift-key and one of said platen and type-bar support members constructed and arranged to shift such member obliquely and in a plane coincident with or parallel to the oblique plane in which the type-bar pivots are situated.
- 15 16. The combination of an endwise-movable carriage, a platen mounted thereon, and movable transversely to the line of travel and obliquely to the horizontal plane of the machine, means for at will so moving the platen transversely, a series of pivoted horizontally-disposed key-levers extending under the carriage and to the front of the machine, a series of type-bars pivoted in front of the platen below the horizontal plane thereof and each of which swings on a single pivotal center, and normally inclined away from the platen toward the front of the machine, a support arranged obliquely to a horizontal plane and on which said type-bars are pivoted, two or more characters rigidly secured to each type-bar and operative connections between each type-bar and its corresponding key-lever.
- 20 25 30 35 17. The combination of an endwise-movable carriage, a platen mounted thereon and movable transversely to the line of travel and in a direction inclined to a horizontal plane,

means for at will so moving the platen transversely, a series of pivoted horizontally-disposed key-levers extending under the carriage and to the front of the machine, a series of type-bars pivoted in front of the platen below the horizontal plane thereof and each of which swings on a single pivotal center, and normally inclined away from the platen toward the front of the machine, a support arranged obliquely to a horizontal plane and on which said type-bars are pivoted, two or more characters rigidly secured to each type-bar and operative connections between each type-bar and its corresponding key-lever.

40 45 50 55 60 18. In a type-writing machine, the combination of a platen, a series of pivoted type-bars each provided with a plurality of types rigidly secured thereto, said type-bars pivoted in an arc which lies in a plane oblique to the horizontal plane of the machine, and being constructed and arranged to strike between the top and front of the platen, a shift-key, and connections between said shift-key and said platen constructed and arranged to enable the platen to shift obliquely and in a plane parallel to the oblique plane in which the type-bar pivots are situated.

Signed in the borough of Manhattan, city of New York, in the county of New York and State of New York, this 17th day of February, A. D. 1900.

BYRON A. BROOKS.
